(57) CLAIM

The ornamental design for an ornamental Christmas tree watering device, substantially as shown and described.

DESCRIPTION

FIG. 1 is a left side elevational view of an ornamental Christmas tree watering device in accordance with the present invention, the right side being a mirror image; FIG. 2 is a rear elevational view of the tree watering device of FIG. 1;

FIG. 3 is a front elevational view of the tree watering device of FIG. 1;

FIG. 4 is a top plan view of the tree watering device of FIG. 1;

FIG. 5 is a bottom plan view of the tree watering device of FIG. 1;

FIG. 6 is a left side elevational view of an ornamental Christmas tree watering device in accordance with a second embodiment of the present invention, wherein the shading indicates red colored stripes similar to candy cane, the right side being a mirror image;

FIG. 7 is a rear elevational view of the tree watering device of FIG. 6;

FIG. 8 is a front elevational view of the tree watering device of FIG. 6;

FIG. 9 is a top plan view of the tree watering device of FIG. 6; and,

FIG. 10 is a bottom plan view of the tree watering device of FIG. 6.

The broken line showing is for illustrative purposes only and forms no part of the claimed design.
